US00D936133S

(12) **United States Design Patent** (10) **Patent No.:** **US D936,133 S**
Desodt et al. (45) **Date of Patent:** **** Nov. 16, 2021**

(54) **BATTERY CHARGER FOR ELECTRONIC EYEGLASSES**

(71) Applicant: **Mitsui Chemicals, Inc.**, Tokyo (JP)

(72) Inventors: **Hortense Desodt**, San Francisco, CA (US); **Thomas Overthun**, San Francisco, CA (US)

(73) Assignee: **Mitsui Chemicals, Inc.**, Tokyo (JP)

(**) Term: **15 Years**

(21) Appl. No.: **29/741,714**

(22) Filed: **Jul. 15, 2020**

(57) **CLAIM**

The ornamental design for a battery charger for electronic eyeglasses, as shown and described.

DESCRIPTION

FIG. 1 is a top front perspective view of battery charger for electronic eyeglasses showing the claimed design;

FIG. 2 is a front view thereof;

FIG. 3 is a rear view thereof;

FIG. 4 is a top view thereof, the bottom view being a mirror image thereof;

FIG. 5 is a right side view thereof; and,

FIG. 6 is a left side view thereof.

The dashed broken lines in the figures show portions of the battery charger for electronic eyeglasses that form no part of the claimed design.

The dot-dash broken lines in the figures show boundaries that form no part of the claimed design.

1 Claim, 6 Drawing Sheets
